UNITED STATES PATENT OFFICE

VICTOR MAUCK, OF MERION, PENNSYLVANIA

GAS WATER HEATER

Original application filed November 24, 1924, Serial No. 752,037. Divided and this application filed April 26, 1928. Serial No. 272,936.

This is a division of my application Serial No. 752,037, filed November 24, 1924, for Letters Patent of the United States, for improvement in thermostatically controlled gas water heaters, which includes claims for the general construction of the combustion chamber herein disclosed; the claims in this case being laid to the means for presenting the water to be heated in a hollow body termed 10 a water spreader supported above and in co-operative relation with a subjacent gas burner.

As hereinafter described, my invention is embodied in a heater adapted to be included in 15 a house water supply system and comprising a container which is a hot water reservoir; constructed and arranged to automatically regulate and maintain a predetermined temperature of the water stored in said reservoir, 20 by varying the supply of gas to a burner in accordance with the temperature of the water in the reservoir; reducing the flow to the minimum when the water reaches such predetermined temperature. The construction 25 and arrangement of said spreader are such as to induce a very rapid circulation of the water in the reservoir to effect correspondingly rapid heating thereof.

In the heater hereinafter described, said 30 water reservoir container has a combustion chamber at the bottom thereof with a flue leading to the outer atmosphere through the container; and the spreader is directly attached to the bottom of the water container 35 so that the cold water flows downwardly into it in a tubular stream around a hot water outlet pipe which is in coaxial relation with the spreader and directs a stream of hot water 40 from the spreader back into the reservoir, within the tubular stream of descending cold water.

My invention includes the various novel features of construction and arrangement 45 herein set forth.

In said drawings; Fig. I is a plan view of a gas water heater conveniently embodying my invention.

Fig. II is a vertical sectional view of said 50 heater, taken on the line II, II in Fig. I.

Fig. III is a plan view of the spreader which is indicated in Figs. I and II.

Fig. IV is a fragmentary vertical sectional view of said spreader and a fragmentary portion of the diaphragm in the heater shell with which it is connected, which forms the bottom closure of the water reservoir and the top of said combustion chamber.

In said figures; the water container comprises the cylindrical metal shell 1, having the cold water inlet 2 and hot water outlet 3 at the top thereof, and the combustion chamber 5 at the bottom thereof. The diaphragm 6 forms the bottom closure of the water space 7 in said container 1, and the top of said combustion chamber. The flue 10 has its lower end connected with said diaphragm 6, and extends to the outer atmosphere, through said water container, parallel with, but eccentric to, the axis of said container shell 1.

The hollow oblate water spreader 11 is mounted in eccentric relation with said diaphragm 6 and extending below the latter in said combustion chamber; having at its upper portion, in coaxial relation, an externally screw threaded neck flange 13 extending in a corresponding opening surrounded by the flange 14 in said diaphragm 6. Said spreader has, in coaxial relation therewith, but eccentric to said container, the socket 15, 75 engaged with the lower end of the hot water riser pipe 16 which terminates in spaced relation with the top of said container shell 1. Said spreader also has two diametrically spaced cold water inlet nozzles 17, at respectively opposite sides of said socket 15 and 80 in communication with the water space 7 through said spreader neck 13.

Said inlet nozzles are preferably disposed 85 in parallel relation with each other and with the axis of said riser pipe 16, as such construction and arrangement have been found to facilitate the circulation of the water from and to said water space 7. The water heated in said spreader tends to circulate therein 90 in the direction of the arrows, as the result of its expansion by the heat, and the parallel arrangement of said inlets tends to facilitate that direction of flow by directing the cold water to the bottom of the spreader im- 100

mediately adjoining the axis of the latter. It was found in practice that when said nozzles 17 were disposed in downwardly diverging relation the cold water issued therefrom in a current opposed to the natural upward current of the hot water and retarded the circulation aforesaid.

The water drain pipe 18 extends from the bottom of said spreader 11 to the exterior of said combustion chamber 5 where it is provided with the drain cock 19, through which sediment may be withdrawn from said spreader. The collar 20 encircles said drain pipe 18, and is provided with the set screw 21 to secure it in adjusted position. The gas burner includes the hollow horseshoe-shaped body 23, having the radially extending cross bars 24 forming axial bearings 25 embracing said drain pipe 18 and resting upon said collar 20. The mixing tube 26 extends from said burner body 23 in eccentric tangential relation thereto but in diametrical relation with said container 1 and combustion chamber 5, as best shown in Fig. I, and 25 is slip fitted over the gas supply tube 27. The arrangement is such that said burner may be readily withdrawn and replaced laterally with respect to said pipe 18 and collar 20 which support it. As shown in Figs. I 30 and II; said mixing tube 26 is enlarged at its outer end and provided with the restricted air inlet 28 at the bottom thereof.

The gas conduit 30 leading to said burner 23 has the automatically, thermostatically, 35 operative valve 31, arranged to control it in accordance with the expansion and contraction of a thermostatic element in the tube 32, which is rigidly connected with said valve. Although any suitable form of said 40 valve 31 may be employed; that indicated is a specific form claimed by Arthur E. Paige, in Letters Patent of the United States No. 1,542,573, granted June 16, 1925.

Said tube 32 extends diametrically in the 45 water space 7 in said container shell 1, between said flue 10 and hot water riser pipe 16, and said valve 31 and tube 32 are detachably connected with said container shell 1 by the screw thread on the valve casing enclosing the spud 33 in said shell.

I also find it convenient to provide said gas supply conduit 30 with the manually operative stop cock 34, leading to said conduit 27, between said automatic valve 31 and said burner 23; and also to provide the manually operative needle valve 35 in said conduit 27 between said stop cock 34 and said burner 23 in cooperative relation with an inlet port in the nozzle 36 which is detachably connected with said conduit 27, in coaxial relation with said mixing tube 26.

It is to be understood that said stop cock 34 may be manually opened or closed, to either permit or prevent the passage of gas through said automatically, thermostatical-

ly, controlled valve 31; the function of the latter being to so regulate and control the rate of flow of gas to the burner 23 as to maintain the water in said container space 7 at a predetermined temperature for which said valve 31 is calibrated. The function and effect of said needle valve 35 is to permit the operator to clean, and vary the effective area of the port surrounding the inner, conical, end of said valve 35, leading through said nozzle 36 directly to the burner.

The heater chosen for illustration is of the type wherein a considerable volume of hot water is stored and normally maintained at a predetermined temperature, say 170° F.; as distinguished from heaters which have a minimum storage capacity and depend for their efficiency upon rapid heating of a minimum quantity of water upon demand. Therefore, it is important to conserve all of the heat generated by combustion of the gas at said burner 23, so as to minimize the quantity required. Therefore, I provide the heat insulating casing for said container and combustion chamber, and including the exterior shell 38, in concentric spaced relation with said container shell 1, and a refractory porous lining 39 for the same, which may be conveniently formed of involutely wrapped primarily plane sheets of corrugated asbestos paper, which form a cylinder filling the space between said concentric cylindrical shells 1 and 38 as indicated in Fig. II. Said heat insulating casing includes the metallic top cover 40 having the 100 refractory lining 41 which may be conveniently formed of the same material as the lining 39. Said casing shell 38 is also provided with the base cover 42 having the opening 43 in coaxial relation with said water container shell 1; affording access to the combustion chamber 5 to permit the operator to adjust and clean said burner 23.

However, if the burner 23 remained thus exposed; a considerable volume and pressure of gas would be required to maintain the burner lighted; whereas, I find that the desired temperature of the stored water can be maintained by the combustion of gas at such a slow rate that it would be impossible to thereby continuously maintain the flames 44 at said burner, if the latter were exposed to any direct air draft. Therefore, I provide a heat insulating closure for said opening 43, including the annular metal frame 45 containing the lining 46 of porous refractory material, conveniently such as above described. Said lining may be formed in semi-circular sections, as indicated in Fig. I, to facilitate its application and removal with respect to said pipe 18. Said closure 45 is detachably connected with said base 42 by the clip 48 which is stationary upon said casing cover 42, and the slide catch 49 which is mounted to reciprocate through the sta-

tionary bight 50 upon said casing cover 42, diametrically opposite to said clip 48. Said base 42 has flanged plates 52 welded thereon to detachably engage the legs 53, by their respective wedge lugs 54.

It may be observed that the construction and arrangement above described are such that the space in said combustion chamber 5 is substantially secluded from the outer atmosphere, by a porous medium excluding all forceful air drafts from said burner 23. The air necessary for combustion is let in to said chamber 5, only through the minute pores of said lining 46 and interstices at the junctions of said closure 45 with said outer casing cover 42; so that small flames 44 may be continuously maintained upon said burner 23 in an atmosphere in which the movement of air is thus so diffused and controlled as to prevent extinction of such flames.

Said heater mechanism operates as follows: Said catch 49 being withdrawn and said bottom closure 45 removed, by lowering it upon the pipe 18 from the position shown in Fig. II, to afford access to the combustion chamber 5, and said needle valve 35 retracted to permit the passage of gas to the burner 23 through said nozzle 36; the gas is turned on by opening the stop cock 34 to the position shown, and the gas ignited at the outlets in the top of said burner 23 to form the flames 44. Thereupon, said closure 45 is replaced and secured as indicated in Fig. II and, by the operation of the thermostatic element 32, affected and effected by changes in the temperature of the water in the container chamber 7; more or less gas is permitted to pass through said supply conduit 30 and the valve 34 and around the valve 35 to said burner 23 to heat the water in said spreader. Owing to the oblate form of said spreader 11, the hot water rises within it to the top thereof and flows upwardly through the riser 16 into said container chamber 7; displacing a corresponding volume of cold water which flows downwardly through said spreader neck 13 and nozzles 17 into contact with the hot lower wall of said spreader, thus circulating the water from said container 1 through said spreader until the desired temperature thereof is reached and maintained.

Of course, said thermostatically controlled valve 31 is operated to gradually diminish the volume of gas permitted to pass therethrough in accordance with the rise in temperature of the water in said space 7, until the minimum is reached which will maintain the desired temperature of the stored water under normal conditions. Under such conditions, the gas flames 44 remain continuously lighted at said burner 23 although they fluctuate in height in accordance with the volume of gas being consumed which, of course, depends upon the rate at which water

is drawn from the space 7 with consequent lowering of the temperature thereof by the influx of cold water through the pipe 2. It may be observed that the latter terminates immediately above said thermostatic element 32 so that the latter is instantly affected by inflowing cold water.

In order to remove said burner 23 without removal of any of the pipe connections, it is only necessary to shift it to the left in Fig. II far enough to release the outer end of the mixing tube 26 from the gas supply tube 27. Said burner may then be partly turned around said drain pipe 18 and withdrawn from the latter.

Although I prefer to conserve the heat in the container and combustion chamber by means of metal members lined with porous refractory material, as above described, and claimed in my copending application aforesaid; any suitable heat insulating means may be employed.

It is the ordinary practice to provide gas water heaters with substantially large openings through which the outer atmosphere may freely communicate with the space in which combustion is affected; upon the theory that such provision for large volumes of inflowing air is essential for the proper operation of a gas burner. As far as I am aware, it is entirely novel and original with myself to seclude such a burner in a chamber from which the outer atmosphere is excluded as above described, regardless of whether such seclusion is attained by refractory means or not. Such combustion chambers are claimed in my copending application Serial No. 752,037 aforesaid.

Moreover, it is the usual practice to provide the mixing tubes leading to gas burners with a series of air inlets encircling the gas inlet; upon the theory that such an arrangement is necessary or desirable to facilitate the mixture of the air with the gas. However, the volume and rate of flow of gas in my improved heater above described, to maintain the stored water at the predetermined temperature aforesaid, are so slight that it was found in practice that such air inlets permitted a considerable portion of the gas to drift, backward, out of the air inlets above the gas inlet and to thus escape, unconsumed, through the flue. Therefore, I found that hermetically sealing the upper portion of the mixing tube 26 and providing a restricted air inlet 28 only at the bottom thereof prevented such escape and waste of gas and caused all of the gas passed by the automatically thermostatically controlled valve to be delivered through the burner and consumed thereat. Although I have found it convenient to form said inlet 28 as a slot extending sectorially in said tube 26; of course, it may be otherwise shaped; the essential feature being that means are provided to her-

metically close the mixing tube around the gas inlet, except for a restricted air inlet below the gas inlet, and it may be observed that said air inlet is at a greater distance from the jet orifices in the top of the burner than said gas inlet. Such burners are claimed in my copending application Serial No. 272,937, filed April 26, 1928, for Letters Patent of the United States.

10 Therefore, I do not desire to limit myself to the precise details of construction and arrangement herein set forth, as it is obvious that various modifications may be made therein without departing from the essential 15 features of my invention, as defined in the appended claims.

I claim:

1. An article of manufacture, consisting of a single hollow metal casting adapted to 20 form a water spreader in a water heater, and having a single cold water inlet in the top thereof merging into a plurality of nozzles projecting into the hollow of said body parallel with the axis thereof, and a single 25 hot water outlet in coaxial relation with said body and between said nozzles.

2. An article of manufacture, consisting of a single hollow metal casting adapted to 30 form a water spreader in a water heater, and having a single cold water inlet in the top thereof merging into a plurality of nozzles projecting into the hollow of said body parallel with the axis thereof, and a single hot 35 water outlet in coaxial relation with said body and between said nozzles, the upper ends of the water passages to said nozzles being oppositely inclined toward the axis of said inlet, and of less radial extent from said axis than the lower ends of said nozzles.

40 In testimony whereof, I have hereunto signed my name at Conshohocken, Pennsylvania, this eighteenth day of February, 1928.

VICTOR MAUCK.
